UNITED STATES PATENT OFFICE.

MAURICE BERNSTEIN, OF SAN FRANCISCO, CALIFORNIA.

REENFORCED PLASTIC CONTAINER.

Application filed March 8, 1922. Serial No. 541,943.

To all whom it may concern:

Be it known that I, MAURICE BERNSTEIN, a citizen of the United States, residing at San Francisco, in the county of San Francisco, State of California, having invented a new and useful Reenforced Plastic Container, of which the following is a specification, in such full and clear terms as will enable those skilled in the art to construct and use the same.

This invention relates to a reenforced papier mâché article and an object of the invention is not only to reinforce such articles in the ordinary way to stiffen them but also to reinforce them in such a manner as to increase their wearing qualities.

It will be understood by those skilled in the art that while it is common to reinforce plastic articles to strengthen them, that many articles subject to wear deteriorate very rapidly after the surface is broken and soon become of no value.

In the present instance an interior reinforcing is provided which is sufficiently close to the surface to prevent the article from wearing away while at the same time it greatly stiffens the article and gives it greater strength.

Other objects of the invention will appear as the description proceeds.

An embodiment of the invention is shown in the accompanying drawings in which the same reference numeral is applied to the same portion throughout, but I am aware that there may be modifications thereof.

Fig. 1 is a perspective view of a tray made of a plastic paper material showing the reinforcing in dotted lines.

Fig. 2 is a sectional view of a portion of the tray shown in Figure 1, and

Fig. 3 is a sectional view of the bottom of the tray shown in Figure 1 on a larger scale.

The numeral 1 indicates the plastic material of the tray, which material is molded into the desired shape to cover the reinforce-

ing. The reinforcing consists in pairs of wires 2 and 3. These pairs of wires extend transversely and longitudinally of the tray and are twisted together as indicated at 4 and 5 to produce elongated loops. At the ends of the tray, the tray may be supplied with twisted wire handles as shown at 6 and 7, said handles being an extension of the interior reinforcing of the tray.

The plastic material is molded over the reinforcing and the molds press the material down tightly at the same time bringing the loops of wire close to the surface of the tray, both interior and exterior thereof. The tray may then be lacquered, and even though the lacquer wears off, the wires are so close to the surface that they will prevent any additional wear on the inside or outside of the tray.

While a tray has been referred to as the construction to which the reinforcing is applied, it will be clear that this reinforcing may be used in conjunction with any kind of a plastic material box, bucket or container.

What I claim is as follows, but various modifications may be made in the construction shown in the drawings and above particularly described form, within the purview of my invention:

An article of the class described comprising a reinforcing consisting of wires twisted together to form elongated loops, and a plastic material forming the article surrounding the reinforcing, the reinforcing being arranged to lie with the loops substantially parallel to the plane of the inner and outer surfaces of the article and closely adjacent the surfaces thereof, whereby upon any wear of the article the loops of reinforcing will prevent undue wear.

In testimony whereof I have hereunto set my hand this 25th day of February A. D. 1923.

MAURICE BERNSTEIN.
